UNITED STATES PATENT OFFICE.

AUGUST F. WEGENER, OF RIDGEWOOD, NEW JERSEY.

DUPPLICATING-MACHINE.

1,243,573.

Specification of Letters Patent.

Patented Oct. 16, 1917.

Application filed February 17, 1917. Serial No. 149,204.

To all whom it may concern:

Be it known that I, AUGUST F. WEGENER, a citizen of the United States, and a resident of Ridgewood, in the county of Bergen and State of New Jersey, have invented a new and Improved Duplicating-Machine, of which the following is a full, clear, and exact description.

This invention relates to a copying or 10 duplicating machine and has particular reference to devices of this character adapted particularly for reproducing any suitable number of copies of sheets of typewriting, manuscript, drawings or the like.

15 Among the objects of the invention is to provide a machine of the character indicated having the maximum simplicity and reliability of operation and hence a machine that may be made and put upon the market 20 at a minimum cost to the public.

Another object of the invention is to provide a duplicating machine of simple construction, but provided with improved means for gripping or holding one end of 25 the sheet so as to increase both the speed of operation and the accuracy of alinement in making the duplicate copies.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

40 Figure 1 is a vertical longitudinal section indicating a preferred embodiment of the invention;

Fig. 2 is a vertical transverse section on the line 2-2 of Fig. 1, and

45 Fig. 3 is a section or detail plan view as seen from the line 3-3 of Fig. 1 with portions broken out.

Referring now more particularly to the drawings, I show a machine comprising a bed 10 having any suitable standards or supports upon which it may be supported in practice. As shown said bed is formed preferably of flat sheet metal having its ends bent into substantial cylindrical drums 11 and 12, said drums being located below the plane of the bed and serving consequently as feet or standards to position the

bed at a desired elevation above the table or the like upon which the machine is operated. Any suitable material may be employed in the construction of this portion of the device, it being essential that such material possesses sufficient stiffness or body to provide ample strength for the work to be performed thereon. As noted substantially in Fig. 2 the side edges of the bed are 60 bent downwardly forming vertical flanges 13 which increase the stiffness of the structure materially. Auxiliary flanges 14 are secured upon the inner faces of the flanges 13, a portion of each auxiliary flange being spaced inwardly from the lower edge of each main flange 13 providing a race way 65 for certain wheels or rollers described below. These auxiliary flanges or strips also add materially to the rigidity of the bed structure. 70

At 15 I indicate a cushion of any suitable non-metallic and preferably of resilient nature, having several important functions. Primarily the cushion serves the usual purpose of a cushion to insure a proper contact or co-operation between the impression roller and the gelatinized film 16 which is generally used over the upper surface of the cushion. Secondly, the cushion being interposed between the bed 10 protects the film from the chill that would result if it were positioned in close contact with the metal body of the bed. 75

In each of the drums 11 and 12 is located 80 a transverse roller 17 or 18. These rollers are adapted to be introduced into the drums and supported therein in any suitable manner. The drum 11 is shown provided with a hinged door 11' for this purpose, while the drum 12 is provided with a similar door 12'. The film 16 above referred to is rolled upon one of the rollers and thus introduced into one of the drums. The free end of the film is then drawn out of said drum as 85 through a passageway 19 and thence over the upper surface of the cushion and thence down through another passageway 20 where it is attached to the opposite roller so as to be rolled upon the latter roller from time to time to present a fresh surface or portion 90 of the film to receive the impression from the original copy to be transferred subsequently to the desired duplicate copies, either roller, especially the latter mentioned one, is provided with a knob 21 for the purpose of manipulating the film. These drums, 105 110

but for their passageways 19 and 20 for the film, and irrespective of their cross sectional form, are substantially inclosed and constitute in effect humidifiers for the film, 5 which from its nature requires for best results to be kept moist. Furthermore, the drums serve to protect the highly sensitive rolls from injury due to dust, impact from outside objects, contact of the operator's hands, etc. The construction of the drums 10 adapts them also for maximum strength and relative lightness.

Along each side of the bed and projecting upwardly therefrom is a rail 22. These rails 15 stiffen the bed and also serve to limit the lateral movement of the cushion and other parts operating thereupon.

Any suitable means may be provided to 20 manipulate the sheets on or over the gelatinized film or its equivalent, so as to effect the transfer of the matter to be reproduced. The means I have preferred, however, for this purpose comprises an impression roller 23 of any suitable construction mounted 25 upon an axle 24, journaled at its ends in a carriage or frame 25 movable to and fro from one end of the bed to the other. The impression roller obviously is intended to bear directly upon the sheet S lying upon 30 the film and between which and the film an impression transfer is to be made as well understood in this art. The frame 25 includes T-shaped extensions 26 on opposite sides of the bed and extending somewhat 35 below the flanges 13 and 14, and each extension is provided with a vertical slot 26' through which the end of the axle 24 projects. Each extension 26 carries a plurality of anti-friction rollers or wheels 27 which 40 roll in the race way formed between the flanges 13 and 14. By this means the upward movement of the frame or carriage is limited positively, but the longitudinal movement of the carriage over or along the bed 45 10 is not materially resisted. On each side of the machine is located a strong coil spring 28, one end of which is secured at 29 to the projecting end of the roller shaft while the other end is anchored at the point 30 adjacent to the lower end of the T-shaped extension 26. The function of these springs 50 is to tend to cause the roller to hug down closely upon the film or sheet S applied thereto and to cause also the ends of the frame to be elevated so as to hold or tend 55 to hold the rollers 27 in their tracks. By providing the slots 26' it is possible for the operator to bear down more or less firmly upon the carriage, as through the handle 60 31, to vary the degree of pressure upon the impression roller. This action of the operator is communicated directly to the lower ends of the extensions 26 and is resiliently resisted by the springs 28. The normal 65 length of the slots 26 above the axle 24

should not exceed the depth of the flanges 13 and 14, whereby it will ordinarily be impossible for the maximum pressure applied to the handle to disconnect the rollers from their tracks.

The tracks for the rollers 27 are extended sufficiently beyond the front drum 11 to permit the roller 23 to come well forwardly over the drum where suitable stop means is employed to limit such movement. The stop means herein indicated consists of a combined cradle 32 and gripper 33. The cradle 70 consists of a semi-tubular or trough shaped member conforming to the curved surface of the roller which is adapted to roll directly 75 thereinto. The lower edge of the cradle is fixed rigidly to the gripper plate 33 and this combined device is adapted to roll or tilt forwardly around the axis of the pintles 33', causing the gripper plate to tilt upwardly as indicated in dotted lines in Fig. 1. The normal position, however, of the gripper plate is as shown in full line in Fig. 1 in direct co-operation with a shelf 34 shown 80 as constituting a portion or extension of 90 the upper part of the drum 11.

The rear portion of the frame 25 constitutes an inclined guide 35 along the lower or front edge of which is an anti-friction roller 36 spaced rearwardly somewhat from 95 the main roller 23. When the roller 23 occupies the extreme forward position with the gripper plate tilted upwardly the guide roller 36 is spaced rearwardly from the gripper plate so as to readily admit the 100 edge of the paper into the space below the gripper plate where it strikes against the shoulder 37. The guide 35 and its roller 36 effectively bridge over the space 19 so that 105 there is no likelihood that the sheet of paper will slip into the drum 11.

In the ordinary practice of this invention the operator maintains his hold upon the opposite or free end of the sheet with one hand, while he manipulates the carriage with 110 his other hand. The moment the carriage is propelled rearwardly, after the paper is inserted, as above described, the gripper plate grips the paper beneath it holding it in predetermined position while the desired 115 amount of tension is maintained upon the free portion of the sheet by the operator's hand while the carriage is projected across the bed. When the carriage has been moved across the bed for its intended purpose and 120 the roller is stopped in the cradle 32, the sheet already treated will be laid aside and a fresh one introduced for a repeated operation which may be carried on most rapidly.

With the carriage arranged as above indicated with the rollers 27 operating in the track ways there is slight danger of twisting or binding of the carriage with respect to the bed, inasmuch as the carriage frame and its extensions are all made sufficiently rigid. 125 130

The front and rear spacing of the rollers 27 with respect to the axis of the impression roller adds to the security of this operation. It may be preferred, however, in some constructions to provide a pair of racks 38 on opposite sides of the cushion 15 with which a pair of gears 39 carried by the ends of the roller are adapted to mesh and whereby any possibility of twisting or binding action 10 of the carriage will be prevented.

I claim:

1. In a duplicating machine, the combination of a flat bed, a film operating over said bed, a pair of approximately closed drums 15 connected to the ends of the bed and constituting supports therefor, means to accommodate the end portions of the film in said drums, and impression means movable along the bed, substantially as set forth.
2. In a duplicating machine, the combination of a bed having downwardly projecting side flanges, auxiliary flanges secured to the aforesaid flanges and coöperating therewith to form reinforcing means for the bed and 25 a pair of track ways, and a carriage movable over the bed, said carriage comprising an impression roller, a rigid frame in which the ends of the roller are journaled, said frame having downward T-shaped extensions 30 operating along said track ways, anti-friction rollers carried by said extensions and rolling in said track ways, and means acting between said impression roller and the frame extensions tending to resiliently 35 hold the impression roller in contact with the bed and said extension rollers in their track ways.
3. In a duplicating machine, the combination with a bed, a sensitized film supported 40 thereon and an impression roller movable to and fro over the bed, of a shelf lying approximately in the plane of the bed and forming a stop for the end of a sheet of

paper to be applied between the roller and the film, a gripper plate coöperating with 45 said shelf to hold the end of the paper, and means coöperating with the gripper plate and the roller whereby the roller causes by direct positive action both the lifting and the depressing of the gripper plate. 50

4. In a duplicating machine, the combination with a frame having at one end a horizontal shelf constituting a paper stop, a bed in approximately the plane of the shelf, a roller movable to and fro over the 55 bed and shelf, a gripper plate coöperating with said shelf and tiltable upwardly along one edge from the shelf to receive the end of a sheet of paper to be treated, said gripper plate being depressible into gripping 60 position by direct contact of the roller therewith, and means connected to the plate providing for the lifting of the plate by action of the roller, substantially as set forth.

5. In a duplicating machine, the combination of a supporting frame, a bed plate thereon, gripping means for the end of a sheet of paper adjacent to one end of the frame, said gripper means including a stationary shelf and a plate tilttable around 70 one of its edges as a horizontal axis above the shelf and in substantially the plane of the bed, a carriage movable to and fro over the bed plate, gripper plate, and shelf, an impression roller journaled in the carriage 75 and movable therewith, a guide roller carried by the carriage in spaced parallel relation to the impression roller, and means connected to the gripper plate whereby in cooperation with the impression roller the 80 gripper plate is tilted upwardly between the impression roller and the guide roller when the carriage is at one limit of its movement to admit the paper between the gripper plate and said guide roller.

AUGUST F. WEGENER.
